CLOTHES SUPPORT BAR

Wayman H. Cornelsen, 1000 E. Broadway,
Fairview, Okla. 73737

Filed Oct. 6, 1966, Ser. No. 4,182

Term of patent 14 years

(Cl. D33—8)

FIGURE 4 is an end view of the clothes support bar shown in FIGURES 1, 2 and 3 as it appears when viewed from one end thereof.

FIGURE 5 is an end view of the clothes support bar shown in FIGURES 1 and 2 as it appears when viewed from an end opposite the end which appears in FIGURE 4.

The design is characterized by the combination of a pair of telescoping members of rectangular cross-section, each of which is provided with a clip and enlarged end cap arrangement at one end thereof, all as shown.

I claim:

The ornamental design for a clothes support bar, substantially as shown and described.
